UNITED STATES PATENT OFFICE.

EDUARD BECKER, OF SOLINGEN, GERMANY.

CORKSCREW.

SPECIFICATION forming part of Letters Patent No. 518,018, dated April 10, 1894.

Application filed June 24, 1893. Serial No. 478,738. (No model.)

To all whom it may concern:

Be it known that I, EDUARD BECKER, a subject of the Emperor of Germany, residing at Solingen, Germany, have invented certain 5 new and useful Improvements in Corkscrews, of which the following is a full, clear, and exact description.

My invention includes a movable frame on the spindle of the screw made in two parts, 10 adapted to clasp or engage the neck of the bottle and a spring between the frame and the handle of the screw arranged to exert its force to draw the cork by moving the spindle through the frame.

15 Figures 1— and 2— of annexed drawings, show respectively a front view and a side view of the cork screw, with the frame closed, while Fig. 3— represents a front view of the same with the frame open.

20 A partly round and partly flat box *b* is adjustably arranged on the shaft *a* which carries the handle *h* at its superior extremity and the screw *a'* at its inferior extremity. The downward motion of the box *b* is limited

25 by a ring *a²* fixed upon the shaft *a*, and if desired I may introduce a spiral spring *f* between the box *b* and the handle *h* which spring is compressed when the screw *a'* is turned into the cork, in order to facilitate the drawing 30 out of the cork. The two arms *b'* to the lower extremities of which are arranged the two half rings *b²*, *b³*, which form a whole ring when brought together, are attached to the flat parts of the box *b* so that they can work like a hinge.

35 The closing ring *r*, the upward motion of which is limited by the two studs *b⁸* of the box, can slide over said half rings *b²*, *b³*, which have a collar or bead shaped piece at their lower extremity.

When the cork screw is used, that is, when 40 the frame or bell is placed over the neck of the bottle, the ring *r* lies over the two half rings *b²*, *b³* and the frame is closed. After the screw has been turned into the cork, whereby the spring is compressed, said cork 45 is drawn gradually into the interior of the frame by reason of the force of the spring. If now the cork screw is turned upside down, so that the handle *h* is below instead of on top, the ring *r* will fall down by its weight 50 and will rest upon the two studs *b⁸*, *b⁸*. The two arms *b'* *b'* will separate at the same time and will assume the position shown in Fig. 3. The cork will be free and will then be easily removed from the screw. 55

Having thus described my invention, what I claim, and desire to secure by Letters Patent, is—

1. In combination the cork screw shaft or spindle the box *b* arranged thereon and having stops *b⁸*, the two arms pivoted to the box and having the stop bead at their free ends and the ring arranged to slide over the arms, substantially as described. 60

2. In combination, the cork screw and the 65 two part frame, comprising the box and the arms pivoted thereto and having two semi-circular parts *b²*, and the clamp ring *r*, substantially as described.

In testimony whereof I have signed this 70 specification in the presence of two subscribing witnesses.

EDUARD BECKER.
